(57) **CLAIM**

The ornamental design for a hole punch jig, as shown and described.

DESCRIPTION

FIG. 1 is a top perspective view for a hole punch jig showing my new design;

FIG. 2 is a top plan view thereof;

FIG. 3 is a bottom view thereof;

FIG. 4 is a rear elevation view thereof;

FIG. 5 is a front elevation view thereof;

FIG. 6 is a left side elevation view thereof;

FIG. 7 is a right-side elevation view thereof;

FIG. 8 is a front sectional view taken along lines **8-8** from FIG. 2 thereof;

FIG. 9 is a front sectional view taken along lines **9-9** from FIG. 2 thereof; and,

FIG. 10 is a right-side sectional view taken along lines **10-10** from FIG. 2 thereof.

The broken lines in FIGS. 1-9 depict environmental subject matter and form no part of the claimed design.

1 Claim, 7 Drawing Sheets
